UNITED STATES PATENT OFFICE.

JAMES LEVER RUSHTON, OF BOLTON, ENGLAND.

PNEUMATIC CONVEYER FOR COTTON AND SIMILAR MATERIALS.

Application filed August 5, 1924. Serial No. 730,167.

To all whom it may concern:

Be it known that I, JAMES LEVER RUSHTON, a subject of the King of Great Britain, residing at Kay Street Works, Bolton, in the county of Lancaster, England, have invented new and useful Improvements in Pneumatic Conveyers for Cotton and Similar Materials, of which the following is a specification.

10 The invention relates to improvements in or relating to pneumatic conveyers for cotton and similar materials wherein a series of delivery boxes are employed and has particular reference to the last delivery box of the series in which it has been found in practice that the large amount of dust and like refuse which is drawn through the revolving cage into the dust receptacle has a tendency to cause said revolving cage and other 15 moving parts to become clogged and consequently inefficient in action.

20 The object of the present invention is to construct the last delivery box of a series in such manner that however great the amount 25 of dust extracted from the cotton or the like, it will be efficiently conducted away into its receptacle, so that the cage will not become clogged.

25 Hitherto the last delivery box has been 30 constructed similarly to the others in the series being arranged in such manner that the dust out of the cotton is drawn through the periphery of a revolving cage and then through the pipe or tube, but for the purpose 35 of this invention the rearmost portion of the revolving cage is furnished with a baffle plate or damper, the arrangement being such that the draught is stopped and dust is prevented from being drawn out through the 40 rearmost side of the cage at the rear of the box.

45 In order to carry away the dust or dirt a tube or chamber is provided at each side of the delivery box communicating with the 50 same and said tubes or chambers communicate with one another at a point to the rear of the delivery box that is to say they merge into one tube which leads the dust away to the dust chamber or receptacle the dust being drawn through the device by the usual fan.

Thus the dirt instead of being carried through the periphery of the revolving cage

is passed around and out at the ends thereof so that the parts cannot become clogged. 55

And in order that the said invention may be more clearly understood and readily carried into effect I will now proceed aided by the accompanying drawings more fully to describe the same. 60

Description of the drawings.

Figure 1 is a plan of the last delivery box of a series constructed according to the present invention. 65

Figure 2 is a side elevation thereof, and

Figure 3 is an end elevation thereof.

Referring to said drawings 1 represents the main conveyer tube to which is connected the front of the delivery box 2 having a revolving cage 3 suitably mounted therein. 70

The cotton is driven from the tube 1 through the entrance 2^a of the box until it is carried by a guide roller 3^a into contact with the revolving cage 3. 75

4 is a stripping roller mounted upon a shaft 5 adapted to revolve in a reverse direction to the revolving cage 3 in such manner as to strip off the cotton from said cage 3 and to eject the same through the swing delivery door 6 at the times desired. 80

5 A baffle plate or damper 7 is mounted at the rearmost side of the revolving cage 3 in close proximity to the periphery thereof, and supported by the arms 8 which are 85 mounted in a central bearing or the like 9 carried by the shaft 10 upon which the revolving cage 3 is mounted, the arrangement being such that the draught of air through the cage 3 is stopped by said baffle plate or 90 damper 7 thereby preventing dust from being drawn through the rearmost side of the said cage 3.

95 A suitably mounted clearer roller 11 is provided, adapted to extend through the cage 3 and to press upon the inner surface thereof at or about the foremost end of the damper 7, for the purpose of clearing cotton and the like from the inner surface of said cage 3.

100 In order to carry away the dust or dirt a tube or chamber 12 is provided at each side of the delivery box 2 communicating with the same around the ends of the revolving cage 3, and said tubes or chambers 12 communicate with one another by means of the 105

tubes 12^a at a point 13 to the rear of the delivery box 2 in such manner as to form a single tube 14 by which the dust or dirt is conveyed to the dust chamber or receptacle by means of the usual fan.

Hand holes with detachable covers α are provided in the walls of the chambers 12 so that access may be had to the interior thereof and to the revolving cage 3 for cleaning and other purposes.

By these means the dirt instead of being carried through the revolving cage 3 is passed around the ends thereof, so that the parts cannot become clogged.

It will be understood that the details of construction may be modified without departing from the principle of the invention.

What I claim as my invention and desire to secure by Letters Patent is:—

- 20 1. A pneumatic conveyer for cotton and similar materials having a delivery box, a supply inlet in said delivery box through which air and material to be treated are drawn, a fixed shaft mounted transversely of said delivery box, a perforated cylinder rotatably mounted on said shaft, a damper lying immediately within said cylinder wall, and having an opening at the front to allow the passage of air into said cylinder, a guide roller transversely mounted in said delivery box adapted to propel the incoming material into contact with said cylinder, a stripping roller below said guide roller rotated oppositely to said cylinder, pivoted doors behind said stripping roller, means for maintaining said doors in contact with said stripping roller and adapted to allow the ejection of
- 25
- 30
- 35

the stripped material from time to time, chambers in said delivery box embracing the ends of said cylinder, air trunks connected to said chambers and to an air exhauster.

2. A pneumatic conveyer for cotton and similar materials having a delivery box, a supply inlet in said delivery box, through which air and material to be treated are drawn, a fixed shaft mounted transversely of said delivery box, a perforated cylinder rotatably mounted on said shaft, a damper fixed upon said shaft and within said cylinder, a guide roller transversely mounted in said delivery box adapted to rotate in contact with said cylinder, and to press the incoming material into contact with said cylinder, a stripping roller below said guide roller rotated oppositely to said cylinder, a pivoted door behind said stripping roller, means for operating said door to allow the ejection of the stripped material from time to time, chambers in said delivery box embracing the ends of said cylinder, air trunks connected to said chambers and to an air exhauster, a clearer roller mounted within said cylinder at the front end of said damper, said clearer roller being in frictional contact with the inside face of said cylinder, and rotated by said frictional contact to remove adhering particles therefrom, hand holes with detachable covers, in the walls of said chambers adjacent the ends of said cylinder.

In testimony whereof I have signed my name to this specification.

JAMES LEVER RUSHTON.
